UNITED STATES PATENT OFFICE

HAROLD MARTIN, OF SOUTHSEA, ENGLAND

RESISTANCE ELEMENT

Application filed March 8, 1921, Serial No. 450,666, and in Great Britain March 11, 1920.

This invention relates to improvements in manometers of the kind in which a U-tube containing mercury or other conducting liquid is connected to the higher and lower pressure regions of a pressure difference device such a Venturi or Pitot tube.

The primary object of the present invention is to provide an electrically operated manometer which can be used for direct reading and/or recording, for remote control purposes.

In order that the invention may be clearly understood and readily carried into effect it is hereinafter described with reference to the accompanying drawings, in which:—

Figure 1 is a side elevation illustrating the general arrangement of a resistance manometer constructed according to this invention, one of the legs of the U-tube being shown in section in order to illustrate the internal construction;

Figure 2 is an inverted plan view of the disc at the lower end of one of the resistance elements;

Figure 3 is a top plan view of the disc at the upper end of the resistance element;

Figure 4 is a detail sectional view of an oil separator adapted for use on each of the limbs of the manometer;

Figure 5 is a diagram illustrating a simple arrangement of the electrical connections, and

Figure 6 is a diagram illustrating these connections arranged in a way which has been found in practice to give good working results.

As shown in Figures 1 and 2 and according to this invention, I arrange within each of the conducting legs a of the U tube, which are preferably of iron, an insulated frame made by means of four iron rods b^2 spaced apart by means of ebonite end pieces q as shown in Figures 1, 2 and 3. Upon these iron rods are threaded a number of, preferably, porcelain or glass beads b' which are so disposed that a length of iron or other suitable wire c which is wound by being laid in the grooves formed by the rounded ends of adjacent beads becomes a regular helix of approximately square instead of circular shape. One end

of this wire c is made fast to a screw or terminal d fixed in the lower end-plate q' , while the upper end is connected to screw or terminal d' fixed into a brass terminal plate which is connected through a phosphor bronze spring e to the main terminal plate f which is completely insulated as indicated in Figure 1 from both the cover plate s and the case of the instrument a . The frame and wire are supported upon or immediately above an ebonite or other suitable insulated distance piece r which is channeled to permit of the free passage of the mercury g . A flanged ebonite insulating sleeve t is also provided for use, more particularly in cases where there is water or other electrolyte above the mercury in the legs of the manometer. The instrument shown, designed for use under high fluid pressure, has suitable rubber jointing and insulating rings at the upper end of each leg between the cover s , the terminal plate f , the insulating sleeve t and the case a . The metal studs which are screwed into the flanged ends of the legs of the manometer case are also insulated by means of ebonite or other suitable sleeves as shown. The pressure difference which it is desired to measure is transmitted to the mercury in the manometer by means of the vertical cocks and T's shown at the top of the instrument which are connected into the cover plates, holes being provided in the terminal plates below them as necessary. Horizontal cocks are for equalizing, testing or draining as necessary when using the instrument. An ebonite or other suitable core b is arranged through the centre of each coil and between the ends plates q simply in order to reduce the quantity and weight of mercury necessary to operate the instrument. Normally with no pressure difference the mercury g is so arranged as to leave an equal portion of the resistance wire of each coil c exposed so that the two coils c can be connected up together with the casing to a suitable source of E. M. F. as a suitable form of electric balance system working on say the potentiometer or Wheatstone bridge principle, or some modification thereof, as indicated diagrammatically in Figs. 5 and 6.

Thus, any relative variation in the level

of the mercury or other conducting liquid g in the legs a of the U-tube will upset the balance of the system and cause a pointer or other indicating or recording arm to be deflected proportionately. Conveniently the indicating or recording part of the manometer may comprise a pair of soft iron needles k as in the working diagram shown in Figure 6 each pivotally arranged at the centre of two concentric coils $i' j', i^2 j^2$ having their axes at right angles to one another. The position taken up by the needles k will therefore depend upon the ratio of the currents which are passed through the two pairs of coils, this ratio varying as the mercury rises or falls in the U-tube under the influence of the fluid pressure-difference device employed. Though a single soft iron needle in conjunction with one pair of ratio coils can be used, as indicated in Fig. 5, wherein i and j indicate the two coils, the advantage of using two needles with two similar pairs of coils, the outer coil of one pair being in series with the inner coil of the other pair, as shown in Fig. 6, is that all errors due to inequalities in the inner and outer concentric coils are thereby eliminated. The two such soft iron needles k would be mechanically linked or connected to a common pointer or recording arm l as shown. In one convenient method of arranging the circuits the free insulated ends of the resistance wires c on the cores in the U-tube would be connected one to the inner coil j' and the other to the inner coil j^2 , the other ends of said inner coils being connected to the outer coils i^2 and i' respectively. The ends of the coils $i' i^2$ would also be connected together and to the case m at the middle of the U-tube or to the mercury inside where a glass or non-conducting U-tube is employed. The source of E. M. F. h would be connected across the ends of the resistance wires c at the top of the legs of the U-tube.

Primarily to ensure good insulation but also in order to prevent corrosion due to electrolytic action, I may, as shown in Fig. 4, arrange oil n on top of the mercury in the legs a , water p providing a suitable seal or trap o for the water p in connection with each of the pressure connections if using the manometer for steam or water measurement.

It will be seen from the foregoing description that the improved electrically operated manometer can be used for a large variety of purposes such as for measuring the flow of steam or water or other fluids, for ascertaining the water level of steam generators, or the level of petrol or other liquids in containers. The measurement of the flow of fluids may be done by means of measuring the pressure difference produced by the flow of the fluid across an orifice, Pitot tube, Venturi tube or the like or by measuring the height of a column of water or other liquid flowing over a weir or notch. It can also be

used to give any desired form of alarm upon predetermined limits being reached. Also for boiler work such a manometer could be made to operate in conjunction with one or more indicators to indicate flow of steam, or level of water at different places say at one point convenient for the stoker and the other in the power station superintendent's office. Obviously also any suitable form of indicating instrument can be used with such an electrically operated manometer.

In ordinary cases it is proposed to use a low voltage, 4 to 8 volt, secondary battery for the current supply to the apparatus. The latter, however, can obviously be operated from an ordinary lighting circuit, if necessary with a suitable resistance such as a lamp inserted so that there is only a comparatively low voltage across the manometer itself. There is no difficulty in making the type of indicator shown into a recording instrument, though a rather more powerful movement would, in this case, be desirable. The arrangements shown in the drawings provide an indicating instrument with a central zero, and with a maximum deflection through an angle of 45 degrees. The lengths of the resistance coils and mercury columns are normally arranged to suit the maximum pressure difference to be measured, but if measuring up to any reduced maximum pressure difference the sensitivity of the indicator can be increased by raising the level of the mercury in the legs of the manometer, providing that the minimum pressure difference which has to be measured is within the reduced range of the manometer resulting from raising the mercury level.

It will also be seen that if it is desired to avoid electrical apparatus and the consequent flow of current inside the manometer, the movement of the spindle, arm, pointer, etc., of any apparatus designed to measure the depth, movement, velocity or flow of a fluid which is normally arranged to operate indicating or measuring gear, may be alternatively or additionally arranged to move a contact relative to a resistance, such movable contact being equivalent to the mercury or other liquid in the above mentioned manometer arrangement and thereby providing the means for deflecting the indicator proportionately to its movement which may be electrically connected up and located in any convenient position.

Obviously, if desired, the movement of the mercury in such a manometer may be measured by means of one coil in one leg only, a suitable indicator being an ordinary ammeter calibrated to operate in series with the resistance coil of the manometer, from a supply, the voltage of which, however, must be quite constant. An arrangement like this, in addition to errors introduced by variations in supply voltage, is also liable to errors due

to resistance of connecting leads, and other parts. With the two coil manometer, in conjunction with the indicator previously described, after once calibrating the indicator to read the difference in heights of the columns of mercury in the two legs, correct readings should always be obtained, and it will be found that the instrument is independent of variations of supply voltage, resistance of leads and other parts.

5 While the resistance coils can be regularly wound upon any suitable insulated core or frame, the frame previously described has been found to overcome difficulties arising out of the tendencies of the coils to retain mercury between them and their supports, and of the supports themselves to become permanently coated with a film of mercury, thereby varying the resistance of the exposed portion of the coil and consequently producing errors.

10 If desired the apparatus described may also be used to measure inclination in which case the manometer casing is fixed to the apparatus, such as a gun, whose inclination or elevation it is desired to measure, or a ship the roll of which it is desired to record. The movement of the manometer legs relative to the mercury columns (which in this case remain level), is indicated or recorded and is a measure of the inclination of the apparatus to which the manometer is attached. When used for this purpose certain parts such as the pressure connections and oil seals, would not be required, nor would any oil or other liquid be required above the mercury in the legs.

What I claim is:—

1. As an article of manufacture, a resistance member for manometers and the like, comprising in combination four rods united to insulating end pieces and extending parallel to each other; a series of non-conducting beads threaded on each of the rods so as to be contiguous to each other and form a continuous series extending for the entire length of said rod, said beads being confined between the insulating end pieces; and a resistance wire wound on the frame provided by the four iron rods, being laid in the grooves provided by the beads and providing a helix-like resistance element of approximately rectangular cross section.

2. In a manometer, a resistance member having wound thereon a resistance wire, said resistance member adapted to be partially immersed in the mercury of the manometer; and a spring at the upper end of the resistance member, said spring being electrically connected with a terminal plate and also being electrically connected with the resistance wire of the corresponding resistance member.

In testimony whereof I have hereunto signed my name.
